UNITED STATES PATENT OFFICE.

CHARLES M. MITCHELL, OF WATERBURY, CONNECTICUT.

DESIGN FOR A GLOBE-HOLDER.

SPECIFICATION forming part of Design No. 12,314, dated June 14, 1881.

Application filed January 3, 1881. Term of patent 7 years.

To all whom it may concern:

Be it known that I, CHAS. M. MITCHELL, of Waterbury, in the county of New Haven and State of Connecticut, have invented a new 5 Design for Globe - Holder; and I do hereby declare the following, when taken in connection with the accompanying drawings and the letters of reference marked thereon, to be a full, clear, and exact description of the same, 10 and which said drawings constitute part of this specification, and represent, in—

Figure 1, a side view; Fig. 2, a view of the portion of the shade-ring flat.

This invention relates to a design for shade- 15 holder or shade-ring such as used around lamp and gas burners to support the shade; and it consists in the ornamentation of the side of the ring, as shown in the accompanying illustration.

20 A is the shade-ring; B B, the arms by which it is supported.

The shape of the tongue is that produced by making a series of round holes below the upper edge, then cutting through from the edge

to the holes, so as to leave an opening into 25 the holes of about one-third the diameter of the holes, then from the opening upward the tongue is cut in the shape of a semi-quarter-foil, the curves at each side springing from the intersection of those sides with the holes at 30 the opening.

I do not broadly claim a design for a shade-holder consisting of a series of tongues or es- 35 calloped-like projections, as such, I am aware, is not new; but

What I do claim is—

The design for shade-holder, consisting of the shade-ring ornamented by a series of circular holes below the upper edge, with openings from the upper edge into the holes, less in width 40 than the diameter of the holes, forming tongues which terminate in a semi-quarterfoil shape springing from the openings, as shown in the accompanying illustration.

CHAS. M. MITCHELL.
